UNITED STATES PATENT OFFICE

2,339,751

ELECTRIC LAMP SOCKET

James F. Beal, Bridgeport, Conn., assignor to The Bryant Electric Company, Bridgeport, Conn., a corporation of Connecticut

Application March 5, 1942, Serial No. 433,482

13 Claims. (Cl. 173—328)

This invention relates, generally, to electric lamp sockets or holders and, more particularly, to a lamp socket or holder for use with electric discharge lamps or devices of the double-ended type having contact pins at each end, of which the fluorescent lamp is one example.

The socket of my invention is particularly adapted for use with small or miniature devices of this kind wherein the spacing between the contact pins thereof is relatively close as compared to the larger sizes of devices although it is not limited to such application.

Heretofore, sockets of this kind have been so constructed that not only right and left-hand sockets were required but also right and left-hand parts were required making it necessary to stock the sockets in pairs and to have separate sets of tools for making the right and left-hand parts.

Therefore, it is one object of my invention to eliminate these disadvantages and provide a socket which shall be of simple and rugged construction and which may be more economically manufactured and used.

Another object of my invention is to provide a socket of the character described which may be used at either end of the lamp to eliminate the necessity for right and left-hand sockets and parts therefor.

Another object of my invention is to provide a socket so constructed that the contact pins of the lamp or other device may be easily inserted and removed therefrom by simple movements and which shall function to positively retain the lamp in the mounted position until manually removed.

Another object of my invention is to provide a socket which shall function to effect a positive balanced grip on the contact pins and in which the grip and contact pressure is not alone dependent on the spring tension or action of the contact members or fingers of the socket.

A more specific object of my invention is to provide a socket wherein a depressible means is utilized to force the contact pins of the lamp into engagement with the contact members of the socket to eliminate the necessity of relying upon the spring action of contact members alone.

Another object of my invention is to provide a socket wherein the depressible means utilized to force the contact pins into engagement with the contact members also functions to eject the pins from the socket when the lamp is released from its mounted position.

A further object of my invention is to provide a socket of the character described which is so constructed that the lamp may be mounted or

removed by a simple rotational movement of the lamp about its axis in either direction after the contact pins enter the socket.

Another object of my invention is to provide a socket wherein the slot for receiving the contact pins of the lamp is open at both faces so that the lamp may be mounted adjacent either face.

These and other objects and aims of my invention will become more apparent from the following detailed description when read in conjunction with the drawing wherein:

Figure 1 is an enlarged exploded perspective view of a preferred embodiment of the invention showing details of the various parts;

Fig. 2 is a view in elevation of the socket in partially assembled form (one body half removed) showing the position of the contact pins on initial insertion into the socket;

Fig. 3 is a similar view showing the lamp pins in their final or fully inserted position;

Fig. 4 is a detail plan view of the mounting bracket of the socket which is also utilized to hold the body halves together; and

Fig. 5 is a view showing how the socket of my invention is utilized.

Referring to the drawing, the socket 10 comprises, generally, a base or body member 11 formed of duplicate body halves 12 and 13 secured together by a mounting bracket 14, a pair of contact members or fingers 15 and 16, a plunger or follower 17 and a spring 18 for the plunger.

The body halves 12 and 13 are preferably of a duplicate or symmetrical construction being formed by molding from a suitable plastic material having the necessary insulating and strength requirements. They are so shaped that when placed together, as shown in Fig. 5, they form a two-piece base or body member of generally hollow construction to receive the contact members and other parts of the socket.

Each of the body halves 12 and 13 is provided on its inside face with a plurality of longitudinal recesses 21, 22 and 23 of such shape as to form channels for receiving the contact members 15 and 16 and other parts of the socket when the body halves are placed together. The outside recesses 21 and 22 are of such shape as to receive and position the contact members 15 and 16, and the middle recess 23 is such as to receive and guide the plunger spring 18. The rib portions 24 and 25, which, together with the outside rib portions 26 and 27, which form the recesses, are of less depth than the outside ribs so that a suitable space or guideway is provided

for the plunger 17 when the body halves are assembled.

Each of the body halves is also provided with a transverse slot 28 in the top face thereof of such width as to receive the contact pins of the lamp one at a time. This slot is widened out below its entrance portion by undercutting the face portion of the body half as at 29 so as to receive both contact pins of the lamp when in a turned or mounting position as shown in Fig. 3. The slot is also of such depth, as shown in Fig. 2, as to receive both of the contact pins in vertical relationship as when they are being inserted into the socket.

It will be apparent that when the body halves 12 and 13 are placed together, a base or body member is provided which is of generally hollow construction, and that the slot 28 extends entirely across the top face and is open at both sides or faces.

The contact members 15 and 16 are preferably of identical and symmetrical construction, and are preferably formed of flat spring material having suitable current conducting qualities. As shown in Fig. 1, the contact members are provided with inturned end portions or lips 30 and 31, relatively long and straight shank portions 32 and 33, and mounting portions 34 and 35, which are provided by bending the ends of the contact members at right angles to their shank portions. The mounting portions are provided with threaded openings 36 and 37 to receive the terminal screws 38 and 39.

The contact members are mounted within the base by attaching their mounting portions 34 and 35 to the foot portions 41 and 42 of the body halves. As shown in Fig. 1, each of the foot portions is provided with transverse grooves 43 and 44, L-shaped recesses 45 and 46 and ledge portions 47 and 48 so shaped and related as to receive the mounting portions 34 and 35 of the contact members.

The contact members are assembled, as shown in Fig. 2 for example, with their mounting portions attached to the foot portions of the body halves and their elongated shank portions extending upwardly within the base, so that the inturned end portions 30 and 31 are positioned adjacent to or immediately below the slot 28, and in such position that the contact pins of the lamp may be inserted therebetween.

In order to provide for urging the contact pins of the lamp into engagement with the contact members, the plunger 17 is so mounted with respect to the contact members that it is engaged by the leading contact pin of the lamp and forced downwardly within the base as shown in Fig. 2. The biasing spring 18 is likewise positioned between the contact members beneath the plunger, and rests upon an abutment 51 which forms the bottom of the recess 23. The upper end of the biasing spring 18 is retained in position by a suitable lug 52 on the bottom of the plunger. As shown in Fig. 2, the sides of the plunger normally engage the inside faces of the contact members and slide thereon. The plunger may be of such width that it places the contact members under a slight tension in order to rigidly retain them within the base.

The various parts of the socket may be assembled by placing the contact members and the plunger and its biasing spring in position in one of the body halves as shown in Fig. 2, and then placing the other body half in position over these parts. The body halves may be secured

together by means of the bracket 14 having a rectangular opening therein to receive the upper portions of the body halves. This bracket slips over the body halves in assembled relation until it reaches the ledges 53 formed by the side portions of the body halves where the side members 54 and 55 thereof may be bent inwardly as shown in Fig. 4 into the intermediate slots 57 in the body halves and the back member 56 also bent inwardly to engage the outside face of the body half. It will be apparent that this aligns and securely clamps the body halves together, and also provides a means for mounting or supporting the socket in a manner shown in Fig. 5.

In using the sockets, they may be assembled or mounted as shown in Fig. 5 upon a suitable supporting member or surface 58 in spaced relation to receive the lamp 59. The contact pins 61 and 62 of the lamp are inserted into the socket as shown in Fig. 2. The plunger 17 has a normal extended position somewhat higher than is shown in Fig. 3. When the leading pin 62 engages the end of the plunger, it is forced downwardly until the leading pin engages the bottom of the slot 28, or at least enters the slot 28 a sufficient distance that the trailing pin 61 is slightly below the ends of the contact members as shown in Fig. 2. When in this position, the lamp may be rotated within the slot until the contact pins are turned to the position shown in Fig. 3. As contact pins move into this position from the position shown in Fig. 2, the plunger 17 moves upwardly under the influence of the biasing spring 18 and finally forces the contact pins into direct contact engagement with the ends of the contact members as shown in Fig. 3. Under normal conditions, as when the contact pins of the lamp are correctly spaced, the contact members will be slightly sprung apart by the force exerted by the spring 18 and plunger 17 as shown in Fig. 3.

When it is desired to remove the lamp, it is simply rotated in either direction, forcing the plunger 17 downward against the force of the spring until one of the contact pins becomes disengaged from its associated contact member. Since the force of the biasing spring is continually applied, the plunger is urged upwardly and functions to eject the contact pins of the lamp from the slot 28. It will be apparent that the plunger functions to urge the contact pins into engagement with the inturned end portions of the contact members so that the grip and contact pressure is not entirely dependent upon the spring action of the contact members.

While I have shown the use of a spring-pressed or biased plunger for accomplishing this result, it will be apparent that the same or equivalent result may be accomplished in other ways. All that is required is a resilient or depressible member which may be urged downwardly by the contact pins of the lamp when the lamp is being inserted into the socket, and which functions to automatically exert an upward force against the contact pins when they have been moved to a lamp mounting position.

In view of the foregoing description, it will be apparent that I have provided a socket construction, particularly adapted for use with miniature lamps, which is not only comprised of a minimum number of parts, but which is made up of substantially identical or symmetrical parts which may be readily assembled to provide a complete socket. Furthermore, in view of the symmetrical design of the socket, it is ap-

parent that it has no right or left-hand parts or positions, and may therefore be used in any desired position without regard to right or left-hand relationships. This results from the fact that the slot for receiving the lamp pins is open at both sides of the socket, so that the lamp may be inserted when positioned on either side of the socket. This not only facilitates the use of the socket, but also makes it more economical to manufacture and use, since it is not necessary to stock sockets in pairs as heretofore. That arrangement of contact members and spring biased plunger, or its equivalent, increases the effectiveness and lift of the socket, since it provides a positive and balanced grip of the lamp pins without subjecting the pins to such strains as might damage the lamp.

While I have disclosed a specific embodiment of my invention, it is to be understood that various changes and modifications thereof may be made without departing from the spirit of my invention as defined in the appended claims.

I claim as my invention:

1. A socket for use with a lamp having a pair of spaced contact pins comprising, a base of insulating material formed of two substantially identical body halves with a slot in a face extending to an edge thereof and of a width to receive either of the contact pins and of a depth to receive both of said contact pins, the opposite walls of said slot being provided with undercut recesses, substantially identical contact members mounted in said recesses and provided with inwardly bent end portions extending toward said slot to engage said pins when the lamp is inserted into the slot and rotated from its position of insertion within said slot, a spring-pressed plunger in said slot for urging the pins into engagement with the finger portions of said contact members, and means for retaining the body halves together.

2. A socket for use with devices having spaced contact pins comprising, a housing having base and body portions with a narrow transverse slot in one face thereof, communicating with a side opening to receive the contact pins of the lamp, a pair of elongated contact members mounted within the housing on opposite sides of said slot and side opening, said contact members having terminal portions anchored in the base portion and free end portions positioned below the slot, and depressible means movably disposed between said contact members and normally extending within the side opening for urging the contact pins of the lamp into engagement with the end portions of the contact members.

3. A socket for use with an electric lamp having a pair of spaced contact pins comprising, a hollow two-piece base member formed of substantially identical body halves and having an opening in a face thereof to receive the contact pins of the lamp one at a time, said opening terminating in an enlarged portion to allow rotation of the contact pins therein, elongated contact members mounted within the base member and having inturned end portions below and on opposite sides of said opening, and a spring-biased plunger mounted within the base member between said contact members disposed for direct engagement with the contact pins to urge the contact pins of the lamp into engagement with the end portions of the contact members.

4. A socket for use with electric lamps having spaced contact pins comprising, a base of insulating material having a transverse slot in a face

thereof and extending downwardly into the sides thereof, the width of the slot in the face being such as to receive a contact pin and the depth being such as to receive both contact pins, said slot being open at both sides and being of such width at the bottom that the contact pins may be rotated therein in either direction after insertion, elongated contact members mounted within the base having inturned end portions extending toward the entrance of the slot to be engaged by the contact pins when rotated and terminal portions at the opposite ends secured to the bottom of the base, and a depressible spring-pressed plunger of insulating material disposed within the base between the contact members for urging the contact pins into engagement with the ends of the contact members, said plunger having a straight upper edge to receive the contact pins.

5. A socket for electric lamps having spaced parallel contact pins comprising, a two-piece body formed of duplicate halves disposed in side-by-side relation and having a plurality of internal channels, said body having a slot in one face with a narrow entrance portion and an enlarged portion open at both sides to receive the contact pins one at a time and permit rotation thereof within the enlarged portion in either direction, contact members mounted in said channels to be engaged by the contact pins when rotated into contact making position, a depressible plunger within the body operable to directly engage the contact pins and urge them into engagement with the contact members, and a mounting bracket attached to the body intermediate its ends, said bracket also functioning to retain the body halves together in operating relation.

6. A socket for electric lamps having spaced parallel contact pins comprising, a housing having base and body portions, said body portion having a slot in the end with a narrow entrance to receive the contact pins one at a time and extending downwardly into the body portion into an enlarged portion of a depth and width to permit rotation of the contact pins therein in either direction, said base having a plurality of internal parallel longitudinal channels communicating with said slot, a pair of flat contact springs each having one end anchored in the base portion and extending through two of said channels to the slot in the body portion, a plunger member slidably mounted within the housing between said contact springs to be engaged by the contact pins, and a resilient member disposed in another of said channels to urge the plunger member toward the slot, whereby said plunger member directly engages the contact pins to urge them into engagement with the contact springs of the socket.

7. A socket for use with electric lamps having spaced contact pins comprising, a body formed of a pair of body halves each having complementary recesses in opposed sides forming parallel longitudinal channels within the body and a slot in the top of the body communicating with said channels, said slot having a narrow opening to receive the contact prongs of the lamp one after the other and being enlarged at the bottom to permit rotation of both contact pins in either direction, contact members mounted within the body in said channels and having their ends adjacent the slots to be engaged by the contact pins when inserted into the slot and rotated, a flat plunger member slidably mounted within the body between the contact members, a spring disposed in another of said channels in a position

to urge the plunger member toward the slot, whereby said plunger member functions to urge the contact pins of the lamp into engagement with the contact members of the socket, and means holding said body halves together.

8. A socket for electric lamps having a pair of spaced contact pins comprising, a two-piece housing formed of duplicate halves each having base and body portions, each of said halves being recessed on one side to provide two outer grooves and one middle groove so that substantially parallel internal channels are provided in the housing, the middle groove being formed by two spaced parallel ribs of less depth than the side ribs forming the side grooves so that a space is provided between the said two spaced parallel ribs of each half when they are placed together, a pair of duplicate contact members mounted in the two outer channels and having terminal portions anchored in the base portion of the housing and free end portions extending through the channels to point adjacent the end of the body portion, said body portion having a narrow transverse slot therein extending into an enlarged portion between the upper ends of the contact members to receive the contact pins of the lamp, said enlarged portion being of such depth and width as to permit rotation of the contact pins in either direction after insertion into engagement with the upper ends of the contact members, a flat plunger member of insulating material slidably mounted between the contact members in the said space provided between the pairs of spaced parallel ribs forming the middle groove of each half, a coil spring positioned beneath the plunger member urging it toward the slot in the end of the housing, said spring-actuated plunger functioning to urge the contact pins of the lamp into engagement with the contact members, and a member encircling said housing halves intermediate their ends for holding them together.

9. A socket for a lamp base having a pair of contact pins comprising a housing, a base-receiving aperture in one wall of said housing, a passage leading to said aperture, a pair of spring contact members disposed at opposite sides of said housing, a plunger normally closing said aperture and movable into said housing a distance greater than the distance between said pair of contact pins when engaged by one of said contact pins as said pins pass through said passage to permit a clockwise or counter-clockwise rotation of the base to engage each contact pin with one of said spring contact members.

10. A socket for a lamp base having a pair of contact pins comprising a housing, a base-receiving aperture at one side of said housing, a passage leading to said aperture, a slide plate normally closing said aperture, a spring contact member disposed at each side of said movable plate, means in said housing for securing one end of each of said spring members, said members having their free ends inturned to provide lips disposed adjacent to said passage, said plate being movable downwardly upon engagement by one of said contact pins a distance sufficient to

permit the disposition of the other of said pins below said lips whereby said base may be rotated in either a clockwise or counter-clockwise direction to bring each pin in contact with a spring member and means for urging said movable plate toward said passage to firmly press each pin in contact with one of said lips.

11. A socket for use with a lamp having a pair of spaced contact pins, comprising a base of insulating material with a slot in a face extending to an edge thereof and of a width to receive either of the contact pins and of a depth to receive both of said contact pins, the opposite walls of said slot being provided with undercut recesses, contact members mounted in said recesses and provided with inwardly turned fingers at their ends extending toward said slot to engage said pins when the lamp is rotated from its position of insertion into said slot, and a spring-pressed plunger in said slot for urging the pins into engagement with the finger portions of said contact members.

12. A socket for use with a lamp having a pair of spaced contact pins comprising a base of insulating material with a slot in a face extending to an edge thereof and of a width to receive either of the contact pins and of a depth to receive both of said contact pins when inserted in a line coinciding with the axis of the slot, the opposite walls of said slot being provided with undercut recesses to an extent to accommodate the said pins after inserted in the slot and rotated through 90 degrees, contact members mounted in said recesses and provided with inwardly turned fingers at their ends extending toward said slot to engage said pins when the lamp is rotated from its position of insertion into said slot, and a spring-pressed plunger of insulating material in said slot for urging the pins into engagement with the finger portions of the said contact members and compressible by insertion of said pins into the socket.

13. A socket for use with a lamp having a pair of spaced contact pins comprising a base of insulating material with a slot in a face extending to an edge thereof and of a width to receive either of the contact pins and of a depth to receive both of said contact pins when inserted in a line coinciding with the axis of the slot, the opposite walls of said slot being provided with undercut recesses to an extent to accommodate the said pins after inserted in the slot and rotated through 90 degrees, said base being formed of duplicate halves with each half provided with contact and plunger channels extending to said slot and together forming locating guides for the contact members, contact members in said channels extending to said recess and provided with inwardly turned fingers at their ends extending toward each other, a plunger of insulating material located in one of said channels and guided by the walls thereof and by said contact members and slide axially of said slot, and a spring urging said plunger toward said fingers to force the pins into engagement therewith.

JAMES F. BEAL.
